UNITED STATES PATENT OFFICE.

HELMER N. THUNE, OF CLIMAX, MINNESOTA.

TIRE GAUGE.

Application filed July 28, 1927. Serial No. 209,014.

The present invention is directed to improvements in tire gauges.

The primary object of the invention is to provide a device of this character so constructed that the same can be set and the tire inflated to the corresponding pressure indicated upon the gauge.

Another object of the invention is to provide a gauge for this purpose constructed in such manner that when the pressure has reached a predetermined point air will escape from the gauge to prevent over-inflation, and at the same time give an audible signal to indicate that the proper pressure is built up in the tire.

Another object of the invention is to provide a device of this character so constructed that it can be used in connection with wheels of various kinds, the construction and arrangement being such that air may be introduced into the tire without operating the gauge, if desired.

In the accompanying drawing:

Figure 1 is a longitudinal sectional view 25 through the device.

Figure 2 is a sectional view on line 2—2 of Figure 1.

Figure 3 is a perspective view of the lever.

Figure 4 is a fragmentary side elevation.

Referring to the drawing, 1 designates a hollow head having a cap 2 threaded thereon and confining a rubber plate 3 provided with a valve seat 4, and cooperating with said seat is a valve disk 5 having a valve stem engaging lug 6 carried thereby. The head 1 terminates in a hollow neck 7 and in which is pivotally mounted a lever 8, said lever having its forward end provided with a head 9 adapted to bear against the disk 5, said head being resiliently maintained engaged upon the disk by the spring 10 which has one end fixed to the lever and its other end engaged with the interior wall of the head 1.

The neck 7 has a threaded extension 11 protruding therefrom and provided with an axial opening 12 in which is slidably engaged a stem 13, said stem fitting in the opening somewhat close, but not too close, to permit air to pass through the opening.

Threaded upon the extension 11 is a coupling 14 having a chamber 15 therein and in which is located a coil spring 16 which engages the valve disk 17 fixed to the lower end of the stem 13, and which serves as a closure 55 for the air entrance end of the opening. A

nipple 18 leads from the coupling 14 and to which an air conducting hose, not shown, is secured for admitting compressed air to the gauge.

The rear end of the neck 7 is provided with an exteriorly and interiorly threaded annulus 19, and having its inner end threaded exteriorly thereon is a barrel 20, while the concentrically arranged tube 21 has its inner end threaded interiorly of said annulus, the annulus maintaining the barrel and tube in spaced relation. A portion of the barrel is shaped to define an indicator 22.

The tube 21 has threaded therein the extension 23 of the plug 24, said plug having a threaded periphery 25 for engagement with the tubular member 26 movable in the space between the barrel 20 and tube 21, the tubular member 26 having a cap 27 threaded thereon and provided with a threaded opening 28, the purpose of which will later appear. Graduations denoting pounds pressure are marked upon the tubular member 26, as shown in Figure 4, to cooperate with the pointer 22. A gasket 20' is provided in the outer end portion of the barrel to prevent sediment, grit and moisture from getting between the barrel and tubular member 26 and into the gauge.

In the forward end of the tube 21 is mounted a hollow piston 29, the forward end of which is closed by a disk 30 having a seat 31 and with which cooperates a ball valve 32, said ball being confined in the cage 33, there being a cut washer 34 fixed thereto. An air inlet 35 is formed in the rear wall of the neck 7 to permit air to enter the piston 29 seating the ball valve in the seat 31. Having its outer end threaded in the opening 28 is a cylinder 36 having slots 37 formed therein and slideable on this cylinder is an outer collar 38 which is connected to an inner collar 39 by a coil spring 40, the collar 38 being fixed to the plunger 41 slideable in the cylinder 36 by a pin 42 which is limited in its sliding movement in the slots 37 of the cylinder 36. The plunger 41 is provided with a pair of resilient arms 43 having latches 44 from their outer ends adapted to meet and be released by the cams 45 mounted in the outer collar 39.

The cylinder 36 is further provided with a pair of slots 46 in which the latches 44 rest and normally interlock with the rear walls thereof. The inner end of the cylinder has secured thereto a plate 47 having openings 48

formed in its periphery for the passage of air into the cylinder.

The plunger 41 has secured thereto the inner end of the stem 49, the outer end of which carries a cup-shaped head 50 which normally closes the outer end of the cylinder 36 and when seated will obviously prevent the entrance of dust, grit, and moisture. A coil spring 51 encircles this stem and has its inner 10 end bearing against the plunger 41 and its other end engaged with an annular shoulder 52 formed interiorly of the cylinder.

Encircling the cylinder and collars 38 and 39 is a coil spring 53 which has its outer end 15 engaged with the extension 23 of the plug 24 and has its inner end engaged with the outer end of the coil spring 54 which is of less strength than the spring 53, the inner end of the spring 54 being engaged with the 20 disk 30. Since the spring 54 is of less strength than the spring 53, it will allow the piston to move more for each pound of pressure than the spring 53 would allow it to move. This will allow for singular graduation 25 up to a certain pressure as the cap 27 which brings the cylinder 36 with it in or out and the barrel 26 will have to be turned around more for each pound, than when at the higher pressure when the spring 53 takes 30 effect and will have to yield.

The plug 24 is provided with an axial bore 55 in order that the cylinder 36 may slide therein during the adjustment of the gauge. It will be apparent that when the head 1 is 35 engaged with an inflation valve of a tire that the valve stem thereof will engage the lug 6, thus unseating the disk 5 and rocking the lever 8, whereupon the inner end thereof will engage the stem 13 to unseat the valve 17 to 40 permit air to pass through the opening 12 and into the tire. Obviously, when the head is removed from engagement with the tire inflation valve stem, the spring 16 and air pressure provided in the chamber 15 will seat the 45 valve 17 to cut off the air supply. Assuming that the tire is under-inflated and it is desired to inflate the same to the predetermined pressure, the cap 27 is rotated which feeds the member 26 and cylinder 36 inwardly or outwardly, owing to its threaded connection 50 with the plug 24, until the desired pounds 55 graduations coincide with the indicator 22. As the air pressure builds up in the tire it will back up into the hollow neck 7 and pass through the inlet 35 and will seat and hold the valve 32 seated, thus exerting pressure upon the piston 29 to force the same outwardly, compressing the springs 53 and 54 until the plate 30 contacts with the outer collar 39 60 and forces the same outwardly against the tension of the spring 40. As soon as the cams 45 fully engage the latches 44 they will be released and the spring 40 will expand, relieving the pressure against the piston and there- 65 by forcing the collar 38 away from the col-

lar 39. The collar 38 carries with it the plunger 41 which is connected to the collar 38 by pins sliding in the slots 37 of the cylinder 36 and this forces the spring 51 to yield and the plunger pushes the stem carrying the cup shaped head 50 out for free escape of air to atmosphere with a hissing sound to indicate that the proper pressure has been built up in the tire. Quick movement of the piston caused by release of the spring 40 will now 70 cause the valve in the piston to engage the plate 47 of the cylinder and the valve 32 will be suddenly moved to a wide-open position. As the air passes into the cylinder 36 it will 75 exert pressure upon the plunger as it passes thereby, thus aiding the compressing of the spring 51 which is a comparatively weak one, but of sufficient strength to force the plunger 41 and collars 38 and 39 forwardly and reseat the same as soon as the gauge is 80 removed from the tire inflation valve. The springs 53 and 54 will return the piston 29 to its normal position and the stiffness of the spring 40 will move the inner collar inwardly by the spring 51 forcing the plunger 85 41 inwardly in order that the latches 44 will again snap into engagement with the slot 46 of the cylinder 36. If it is desired to ascertain the air pressure in a tire the head 1 is 90 engaged with the tire valve to open the seat 95 4, but at a pressure which will not rock the lever 8 sufficiently to open the valve 17. In case the tire has been previously over-inflated the gauge will open to permit the escape of 100 excess pressure. Of course, if it is then desired to inflate the tire the head is pressed with sufficient force upon the tire valve to cause the lever to open the valve.

Having thus described the invention, what I claim is:

1. A device of the class described comprising a tube having a hollow piston slidable therein, springs to yieldably hold said piston against compression, a valve in the piston, a cylinder adjustably mounted in the tube, a stem carried by the plunger and having a head thereon for normally closing the outer end of the cylinder, means for interlocking the plunger with the cylinder, and means associated with the cylinder for engaging the valve of the piston to permit air to pass by the plunger when the said plunger and valve are unseated.

2. A device of the class described comprising a tube, a hollow piston slidable in the tube and having a valve carried thereby, means for conducting air into the tube for action upon the piston, a tubular member threaded upon the tube, a cylinder in the tube having a plunger slidable therein, latches carried by the plunger for interlocking engagement with the cylinder, and means controlled by the outward movement of the piston for releasing the latches to relieve pressure against the piston by release of yield-

able means and simultaneously unseat the valve of the piston to permit air to pass therethrough into the cylinder.

3. A gauge of the class described comprising a tubular member, means for conducting air into the member, a piston slidable in the member and having a valve carried thereby, a plug engaged in the end of the member, a spring in said member between said piston and plug to control movement of the piston, and being securely fastened to a cylinder mounted in the tube and slidable in the plug, a plunger slidably mounted in the cylinder and provided with a transverse pin to hold 10 and relieve yieldable means, by its connection to the outer collar and slidable in slots in the cylinder to control movement of the plunger, a head carried by the outer end of said plunger for normally closing the outer end of 15 the cylinder, said plunger having latches carried thereby for normally interlocking engagement with the cylinder, a collar slidable upon the cylinder and having cams carried thereby for engagement with the latches to 20 release the same to permit the plunger to slide to relieve compression of yieldable means against said collar and piston, and means carried by the cylinder for unseating the valve of the piston when the cams of the collar release the latches.

4. A gauge of the class described comprising a barrel, a tubular member disposed concentrically with respect to the barrel and engaged with the annulus, a hollow piston slid-

able in the tube and having a valve carried 35 thereby, means for conducting air from the neck into the member, a plug threaded in the end of the member, the barrel and tubular member having cooperating means for indicating pounds pressure, a cylinder slidable in 40 the plug and having inner and outer collars associated therewith, yieldable means connecting the collars, the outer collar and plunger having connection by a pin, the inner collar having cams carried thereby, a 45 plunger slidable in the cylinder and having a stem provided with a head for normally closing the outer end of the cylinder, a spring encircling the stem and interposed between the plunger and shoulder in the cylinder, resilient arms carried by the plunger and having latches carried thereby for normally interlocking engagement with the cylinder, a 50 plate carried by the cylinder for engagement with the valve for unseating the same when the piston is forced outwardly by air pressure, and means carried by the piston for moving the inner collar outwardly to cause the cams carried thereby to release the latches to 55 permit the expansion of said yieldable means, causing a quick move of the piston and causing movement of the plunger and its stem outwardly to permit the head to disengage the outer end of the cylinder, and springs controlling the movement of the piston. 60 65

In testimony whereof I affix my signature.
